A. MAUSER

CONTAINER

Filed Dec. 12, 1925

INVENTOR

ALFONS MAUSER

BY

P. K. Neumann & Farley
ATTORNEYS

UNITED STATES PATENT OFFICE.

ALFONS MAUSER, OF COLOGNE-MARIENBURG, GERMANY.

CONTAINER.

Application filed December 12, 1925, Serial No. 74,993, and in Germany August 17, 1925.

My invention relates to containers for solid substances or liquids and particularly such as are intended to be closed substantially airtight to preserve the contents during storage or shipment. The object is to provide a strong container with an improved construction for holding the lid in the sealing position. The device not only prevents the escape of the contents, but at the same time guards against the entrance of injurious foreign matter, such as dust or liquids. The particular improved construction by which I obtain these results will now be described in detail with reference to the accompanying drawings in which three satisfactory and preferred embodiments of the invention are illustrated. Fig. 1 is a partial longitudinal section of the container; Fig. 2 is an end view thereof; Figs. 3 and 4 are views similar to Fig. 1 illustrating further embodiments of my invention.

The body or shell A of the container is generally cylindrical or substantially so, the container therefore having the shape of a barrel or drum. Sheet iron or any other suitable material may be employed in the construction of this body. As shown in the drawings, the shell A is made with an inwardly extending annular fold or projection b which serves as a support or backing for a flat ring a constituting a cover support and located toward the open end of the container. The material of the shell is provided with a return-bent portion c toward the open end of the container, said portion being extended inwardly until it is in contact with the flat ring a on the surface thereof opposite to the one engaging the fold b. At f I have indicated a removable cover which may be of any suitable construction, the outer portion of this cover overlaps the ring a and bears against an elastic expanding ring h of the split type, which latter is fitted within the end of the container, and in the closed condition of the receptacle engages an inwardly extending flange at the free end of a ring g which also has an inwardly extending flange at its other end fitted against the fold b at the junction of its two layers. A packing ring d of any suitable material is fitted around the cover in the annular space between the cover support a and the expanding ring h, the packing material thus engaging the peripheral surface of the cover, as well as the cover flange, and also engaging the cover support a and the return-bent portion c of the shell. By virtue of this arrangement a very secure and tight joint is obtained, preventing the entrance of any foreign matter into the container, as well as the escape of any of the contents. It will be understood that the expanding ring h may be contracted sufficiently to pass through the opening at the free end of the ring g and that upon releasing the ring h it will expand to the position shown to hold the cover in the sealing position.

The cover support a, of rectangular cross section, as shown, may be made entirely flat as in Fig. 1, or in addition to this flat portion, the cover support may be provided with an outwardly extending flange a', fitted between the end of the shell and the return-bent portion c, as shown in Figs. 3 and 4. The return-bent portion c may terminate at the outer surface of the ring portion a, having edge contact therewith only as in Fig. 1, or this return-bent portion may be provided with an inward extension such as c' in Figs. 3 and 4, said extension being in contact with the outer surface of the ring portion a. To obtain still better contact and greater security in sealing the container airtight, a flange c² may be provided at the inner end of the extension c' to fit into the opening of the ring portion a, as shown in Fig. 4. In each of these constructions the packing ring d seals not only the opening of the container, but also the joint which the return bent portion c forms with the cover support. In each of these constructions also, the return bent portion c is extended into contact with the ring portion a of the cover support.

Various changes in the specific forms shown and described may be made within the scope of the claims without departing from the spirit of my invention.

I claim:

1. A container comprising a shell having an inwardly bent projection at a distance from its end, and a return-bent end portion located on the inside of said shell, a cover support clamped between said projection and said return-bent portion, a reinforcing ring surrounding said return bent end portion of the shell, having a flange projecting inwardly at the extremity of the shell, in engagement with the bend of said portion and an inturned lip engaging with and covering the outer part of said inward projection, whereby said reinforcing ring is secured upon

said shell in interlocking engagement with, and protects, said portion and projection against shocks or blows, an expanding ring fitted within the shell in engagement with 5 said flange, a cover fitted between said expanding ring and said support, and a packing ring engaging said cover and the return-bent portion of the shell and preventing leakage between said shell and cover support 10 port from the interior of the container to the exterior thereof.

2. A container according to claim 1, in which the cover support has a flat ring of rectangular cross section engaged by the 15 edge of the return-bent portion on that surface of the ring which is opposite to the inward projection of the shell.

3. A container according to claim 1, in which the cover support has an outwardly 20 extending flange fitted between the return-bent portion and the body of the shell.

4. A container according to claim 1, in which the return-bent portion is provided with an inward extension in contact with 25 the surface of the cover support opposite to that which is seated on the inward projection of the shell.

5. A container according to claim 1, in which the return-bent portion is provided 30 with an inward extension in contact with the surface of the cover support opposite to that which is seated on the inward projection of the shell, and in which the inner edge of said extension is provided with a 35 flange projecting into the opening of the annular cover support.

6. A container comprising a substantially cylindrical shell having one end thereof open 40 for a detachable closure, said shell being provided with an inward projection located at a distance from said open end and a return bend extending inwardly of said shell at said end, a cover support clamped between said bend and said projection, a reinforcing 45 ring surrounding the end portion and covering said projection and said return bend, said ring having an inwardly

projecting flange spaced from said cover support, a packing mounted upon said cover support, a cover having an annular flange 50 projecting over said cover support and resting on said packing and a resilient split retaining ring projecting under the flange of said reinforcing ring to clamp said cover securely upon said packing. 55

7. A container comprising a substantially cylindrical shell having one end thereof open for a detachable closure, a closure supporting ring secured in interlocking engagement with the walls of said shell, a cover mounted upon said ring, a packing interposed between said cover and ring, and means to secure said cover detachably in position, the end of said shell interlocked with said ring being located adjacent to said packing 60 whereby said packing serves not only to provide a seal for said cover, but also to seal the joint between said ring and shell and prevent leakage through said joint.

8. A container comprising a substantially cylindrical shell having one end thereof open for a detachable closure, said shell being provided with an inward bend located at a distance from said open end, and a return bend extending inwardly of said shell at 70 said end, a cover support clamped between said bends and having a horizontally extending flange for the reception of a cover and a packing therefor, said inward bend of said shell terminating in contacting engagement 75 with said cover in a position such that leakage of the container's contents between said shell and cover support will be prevented by said packing, and a reinforcing ring encircling said shell and having a pair of inwardly extending spaced flanges interlocked with and surrounding said bends for locking said ring securely to said container and for protecting said bends from external shocks or 80 blows. 90

In testimony whereof I have hereunto set my hand.

ALFONS MAUSER.
